(57) **CLAIM**

The ornamental design for a concave wheel face, as shown and described.

DESCRIPTION

FIG. 1 is a front isometric view of a concave wheel face according to the new design.

FIG. 2 is a front elevational view of a concave wheel face according to the new design; and,

FIG. 3 is a side view of the concave wheel face according to the new design.

The remaining side, top, and bottom views are identical to FIG. 3 except for the placement of the holes.

The characteristic feature of the design resides in the annular outwardly concave surface in which the larger radially outwardly disposed openings are present as shown in FIGS. 1-2 with the curvature best seen toward the front portion of FIG. 3.
